UNITED STATES PATENT OFFICE.

THOMAS S. NICKERSON, OF NEWBURYPORT, MASSACHUSETTS.

CONTINUOUS MUFFLE-KILN.

SPECIFICATION forming part of Letters Patent No. 760,551, dated May 24, 1904.

Application filed August 19, 1899. Serial No. 727,764. (No model.)

To all whom it may concern:

Be it known that I, THOMAS S. NICKERSON, of Newburyport, in the county of Essex and State of Massachusetts, have invented certain 5 new and useful Improvements in Continuous Muffle-Kilns, of which the following is a specification.

This invention relates to kilns, and more particularly to that class designated as "continuous muffle-kilns," and is expressly designed for baking light pottery or tiles, enameling or glazing articles of clay or metal, and for firing overglaze or underglaze decorations on china, pottery, or other ware.

The invention has for its object to provide certain improvements in muffle-kilns to simplify their construction, enhance their efficiency, and increase their convenience of operation and their economy, and, further, to provide a certain construction and arrangement of parts whereby the temperatures of the several compartments may remain constant and be sustained indefinitely and wherein the various processes of ceramic work can be performed either singly or simultaneously.

To these ends the invention comprises certain improvements which are illustrated on the drawings and which I shall now describe and claim.

Of the accompanying drawings, forming a part of this specification, Figure 1 represents a side elevation of a kiln embodying my invention. Fig. 2 represents a longitudinal section on the line 2 2 of Fig. 3. Fig. 3 represents a transverse section on the line 3 3 of Fig. 1. Fig. 4 represents a section on the line 4 4 of Fig. 3. Fig. 5 represents a section on the line 5 5 of Fig. 3. Fig. 6 represents an end elevation. Fig. 7 represents a section on the line 7 7 of Fig. 3. Figs. 8, 9, 10, and 11 represent views of the means for introducing the material to be treated to the interior of the kiln.

The same letters of reference indicate the same parts in all the figures.

In carrying out my invention I provide a kiln *a*, having a series of furnaces *b* *b*' arranged to communicate with flues or passages *c* intermediate of the furnaces and the chimneys *d* *d*'. Said flues or passages pass around

chambers *e* *f* *g* in the interior of the kiln and communicate heat from the furnaces thereto. The chambers *e* and *g*, as shown in Fig. 3, extend laterally of the kiln and are adapted to contain tracks *h* for the reception of a plurality of cars *h*', which operate as a transfer arrangement for introducing the material to the different compartments of the kiln. The chamber *e* has at its ends passages *i* and *j*, adapted to receive a car or vehicle *k*, upon which the material to be treated is placed and which is conducted to the passages by a suitable track (not shown) and passed through them on the tracks *k*' therein.

As said, the kiln is provided with a central elongated chamber *f*, which communicates at either end with the chambers *e* and *g*, being provided with a track *h*², which permits the passage of a vehicle thereon between the last-mentioned chambers. The latter is also provided with a transfer car or vehicle *h*³, the purpose of which will be hereinafter explained.

The central chamber *f* is provided with vertically-movable partitions *l*, adapted to be raised and lowered by any suitable means, here shown as provided with a chain *m*, Fig. 5, one end of which is secured to the upper portion of the partition and the other end secured to one arm *m*' of a double segment *m*². From the other arm *n* of the segment depends a counterweight *o*, Fig. 5, secured thereto by a chain *p*, the arrangement being such that the weight *o*, being but slightly lighter than the partition, permits the latter to be readily raised and lowered.

By the above-described arrangement of the partitions the chambers may be separated or may communicate, whereby the attendant is enabled to vary the degree of heat in the different compartments to suit the work being performed.

In Fig. 7 I have shown a transverse longitudinal section through the chamber *e*, in which is shown the arrangement of one of the furnaces *b* and its relation to said chamber. A passage *c* surrounds the chamber and communicates with the furnace at either end thereof, so that the products of combustion may entirely surround the chamber previous to escaping through the chimney *d*'. A suitable

- damper or register q is operated by a rod r to open or close the chimney-flue s to regulate the combustion of the fuel in the furnace b and vary the temperature of the chamber. 5 Peep-holes t are provided, through which the attendant may be enabled to inspect the condition of the furnace or chamber and also to move the transfer-car by means of a suitable implement, such as a rod, &c.
- 10 In Fig. 4 I have shown a cross-sectional view through the central chamber f and one of the furnaces b' , connected therewith, together with the main chimney d and passages c , intermediate of the latter and the furnace. 15 The furnaces b' under the central chamber f (of which I have shown three, although I may have any suitable number) are connected by the flues c to the chimney d , the passages surrounding the chamber f being substantially 20 similar to those shown in Fig. 7, with the exception that the three furnaces b' are connected with one chimney d , the two outer furnaces b' each having laterally-extending flues $b^3 b^3$, leading to the chimney d . Suitable dampers 25 q' serve to regulate the draft in furnaces b' , and peep-holes b^7 are arranged in connection with the central chamber, so as to enable the attendant to see the material being treated.

The vertically-movable partitions l are 30 adapted to move in a guide v , projecting upwardly from the body of the kiln and having an opening s , through which the chain passes at the top thereof. When the partitions are lowered to subdivide the chamber f , the openings are closed to prevent the escape of heat 35 by a cap u , adjustably secured to the chain m by a set-screw v' or other suitable means.

w , Figs. 2 and 6, represents a door which 40 closes an opening w in the end of the kiln, said door having a peep-hole through which a rod is introduced to move the cars from the transfer-car h' into the chamber f .

A similar arrangement to the above is provided in connection with the chamber g , by 45 which the cars are drawn from chamber f onto the transfer-car h^3 in chamber g .

The material to be treated, as before stated, is placed upon a suitable car k , Figs. 8 and 9. Said car is provided with a series of plat- 50 forms y for the reception of the tile or other material to be treated.

h' , Figs. 10 and 11, represents a car adapted to support a track h^7 upon a suitable frame h^8 and having truck-wheels adapted to engage 55 the rails h in the chambers e g . The track h^7 is mounted upon the car so as to register with the tracks in the passages i j and are adapted to receive the car k therefrom, the arrangement being such that when the car k 60 is placed upon the track h^7 the car h' is moved laterally, so as to register with the track h^2 in the chamber f and the car k is transferred thereto, as shown in dotted lines in Figs. 2, 3, 4, 5, and 7.

65 By the system of independent fire-boxes,

flues, dampers, and drop-doors I am able to keep the temperature of the several chambers and sections of chamber f at different degrees, ranging from a moderate drying heat in the passages of chamber e to the fusing-point of 70 enamels in the center of chamber f . After the kiln is once heated to the proper temperature the requisite heat can be retained in the various chambers with very little fuel, an intelligent use of the dampers q and q' enabling 75 the attendant to force the heat from the furnaces through the walls of the muffle.

The method of operating the kiln is as follows: A loaded car k is introduced through the door into passage i or j and subjected to 80 a moderate heat. After receiving a proper amount of drying it is propelled, by means of a rod passed through a peep-hole in the door of i or j , onto the transfer-car h' , and into the passage just vacated by the first car a second 85 car is entered. By the use of two transfer-cars on track h in chamber e four cars can thus be kept subject to heating preparatory to introduction into the divisions of the long chamber f . When the car k on transfer h' 90 has received the proper temperature, the transfer-car h' is pushed half-way across chamber e by the use of a rod inserted through peep-hole t until the tracks h^7 register with the tracks h^2 in chamber f , in which the drop-doors l are all down. The first door l is then 95 raised and the car k is pushed off from the transfer-car h' onto the track h^2 in chamber f by means of a rod inserted through the peep-hole in door w . The first door l is then 100 dropped and the transfer-car h' is drawn back and is ready to receive the car which has been standing in the passage i or j , and a new car is introduced from the outside to take the place of the latter. When the car in the first division of chamber f has received the proper temperature, as observed through peep-hole b^7 , the 105 first and second doors of the chamber f are raised and the car is propelled by means of a rod operated through a peep-hole in door w 110 into the center section of chamber f , where it receives the amount of heat necessary to properly bake, enamel, or fire the articles under treatment. After the introduction of 115 said car into the central section of chamber f the second door l is dropped and another car is introduced into first section of f from the transfer-car h' in chamber e by the process already described and the first door l is dropped. When the articles on the car in 120 the central section of f have been properly baked, enameled, glazed, or fired, as the case may be, the third and fourth drop-doors of chamber f are raised and the car is withdrawn from the central section by means of a rod inserted through a peep-hole in the door of chamber g , corresponding with door w in chamber e , into the third section of f 125 and the third and fourth doors l are dropped, where it is left until the car which succeeds 130

it in the central section of *f* requires in its turn to be withdrawn. At that time the drop-door No. 4 is raised and the car in the third section of *f* is drawn off onto the transfer *h*³ in chamber *g* by means of a rod inserted in the end door and the transfer *h*³ is drawn over by means of a rod inserted in peep-hole *t*, so that the rails of the transfer register with the tracks of the passages issuing therefrom.

5 The car *k* is then drawn from the transfer by rods or endless chains into the passages or cooling-leers, which are of sufficient length to allow the articles on the car to thoroughly cool before being taken into the open air.

10 It will be observed that each of the elongated or cross chambers *e* and *g* extends both sides of the line of the central partitioned chamber, and each of said cross-chambers has a passage, as *i* and *j*, provided with tracks and 15 communicating with the side of said cross-chamber opposite to the connection of the latter with the central chamber. Therefore a car may be inserted or discharged through either of the passages, so that if it be desired 20 that a particular car shall remain for a longer time subjected to heat in one of the cross-chambers such car may be left in one of said passages or in the projecting portion of the cross-chamber opposite such passage, while 25

25 the other of the pair of entrance or exit passages may be utilized for the continuous operation hereinbefore described. Owing to the fact that each cross-chamber has tracks and a furnace independent of the means for heating 30 the compartments of the central chamber, the relative predetermined degrees of temperature may be better obtained than where a single furnace for the entire series of chambers is employed or where the furnaces are 35 employed only for a central chamber or series of central chambers.

35 This construction is especially useful in the firing, &c., of fine ware, where the degree of temperature applied is of the greatest importance. As will be obvious, the laden car being moved from one compartment having a 40 predetermined temperature to one of higher or lower temperature, as the case may be, the succeeding compartment also having its temperature known, the operator is able to not 45 only insure the proper firing, &c., but the successive cars or trucks being passed through the same temperature a surety is had that the product will be uniform in all respects. Furthermore, as necessity may arise the temperature in the separate compartments may be varied, either by the use of the dampers or by 55 an increase of the heating medium, without materially affecting the temperature of the adjacent compartments, so that where it is desired, for instance, to change the temperature of the compartment between the first compartment and the compartment of highest temperature to a higher or lower degree, as the 60 material operated upon may best need, such

change can be readily made without affecting the temperature of the middle or end chambers or compartments, thereby, in effect, providing means for independently controlling the temperature of the several compartments, 70 a result not possible where a single heating-chamber is used from which the heat is led around the adjacent compartments to the point of exit, thus heating the adjacent chambers to less degree of temperature than the chamber being primarily heated—this for the reason that in the latter case any attempt to vary the temperature of the adjacent chambers would result in changing the temperature of the primarily-heated chamber, the relative degrees of temperature in the several chambers being maintained through the several changes in temperature which might be made.

75 As one car succeeds another closely in the various chambers, the kiln is kept constantly 80 filled, and a fresh car enters the kiln whenever a car-load of finished articles is withdrawn from the cooling chamber or leer.

Having thus explained the nature of the invention and described a way of constructing 85 and using the same, although without having attempted to set forth all of the forms in which it may be made or all of the modes of its use, I declare that what I claim is—

90 1. A kiln of the character specified comprising a heating-chamber having a track, a furnace for continuously heating said chamber to a predetermined high temperature, a chamber elongated from front to rear and adapted to receive the articles to be initially heated, a 100 cooling-chamber elongated from front to rear, each of said last-mentioned chambers having an independent furnace, and each of said last-mentioned chambers having a plurality of inlets each inlet having a track, there being normally closed apertures leading from said heating-chamber to each of the elongated chambers, and devices for transferring cars from one track to another, whereby articles may be initially heated in one chamber, heated to the maximum degree of temperature in the second chamber, and cooled in and discharged from the third chamber without lowering the temperature of the said second chamber.

110 2. A kiln of the character described comprising a series of heating-chambers of substantially equal lateral width, each of said chambers having a track running longitudinally of the chamber, the tracks of the several chambers being in alinement, a chamber 120 located at each end of said series of chambers, each of the end chambers being elongated from front to rear and each having a track extending longitudinally of the chamber and at an angle to the tracks of the series of chambers, movable doors located between each of the said chambers and end chambers, whereby each chamber may be made independent of the adjacent chambers, an independent furnace for each of said chambers and end cham- 130

bers, said furnaces continuously heating the chambers to predetermined high temperatures, a transferring device located on each of the tracks of the end chambers, and a plurality of inlets leading to said end chambers, said inlets having tracks in parallelism with the tracks of the series of chambers.

In testimony whereof I have affixed my signature in presence of two witnesses.

THOMAS S. NICKERSON.
